UNITED STATES PATENT OFFICE.

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK.

VALVE ENGINE FOR STEAM HEATING.

Application filed February 16, 1922. Serial No. 536,876.

For a detailed description of the present form of my invention, reference may be had to the following specification and to the accompanying drawings forming a part thereof, wherein

Fig. 1 is a plan view of my device;

Fig. 2 is a longitudinal section;

Fig. 3 is a perspective of it in operating position and

Fig. 4 shows the thermostat.

My invention is particularly designed for the automatic determination of car temperature in a railway car that is steam-heated by the vapor system, but it may be used in other situations to which it may be applicable. In brief I provide a reciprocating fluid-pressure engine which is applied to the central valve of a vapor system, this engine being normally biased to maintain vapor on the heating pipes and being dominated by an electromagnetic valve which is in turn dominated by a magnet contained in a thermostat case and having its circuit opened and closed by the thermostat.

Referring to the drawing, G is the control valve of a vapor system which admits steam to the heating pipes G⁵ of a car from the train pipe G¹ after it passes through the reducing valve G² which is operated by the outlet thermostat G³ through the agency of an angle lever G⁴, the outlet thermostat being subject to the outflow from return pipe G⁶ of the heating system. The stem F of the valve G is squared at its upper end. Above the valve G I mount a horizontally reciprocating engine having a vertically disposed rotatable shaft E which, at its lower end has a square socket that fits over the square end of the aforesaid valve-stem F and at its upper end is

provided with a handle H. In the event of air-pressure being lacking when the valve G is to be operated, the handle H may be employed for turning it, which also works the engine, since the engine shaft E intervenes between handle H and the valve-stem F. On said shaft E is a pinion D which is engaged on one side by a horizontally disposed reciprocable rack C which has at its respective ends the large piston A in cylinder 3 and the small piston B, in cylinder 4. Between the two pistons is a neutral chamber 2 through which the rack C extends and which contains a supply of grease or oil for lubrication. On the outer end of cylinder 4 is screwed a cap

J with an intervening gasket 8 and on the outer end of the larger cylinder 3 is screwed a cap K with an intervening gasket 7. The cap K has an outward extension K¹ against which is seated the flat side of an electric-valve casing with an intervening gasket 6 and secured by screw-bolts 5, 5. Inside of the said casing is the magnet coil M. The core 16 of the magnet is centrally perforated and through it passes a vertical valve-stem 18 carrying at its upper end an armature 15. At its lower end is an exhaust valve 12 which seats and closes downwardly, and a supply-valve 11 which seats and closes upwardly. The valve-stem 18 is normally held in its uppermost position by means of a spring 10, together with the back pressure of the air, and in this position the exhaust-valve 12 is open and the supply-valve 11 closed. In the engine wall is a duct 9 which is in constant communication with the air supply by means of a port L. At one end of this duct 9 is the aforesaid supply-valve 11, the opposite end being permanently in communication with the rear of cylinder 4. Between valves 11 and 12 a duct 13 leads to the rear of cylinder 3.

The thermostat, as appears in Fig. 4, comprises a mercury thermometer R secured inside a metal shell a mounted on a box-base T of insulation. The bulb of the thermometer is enclosed by a thin metal sheet b which extends to the outside of shell a but is heat-insulated therefrom. By this means the thermometer responds instantly and accurately to the outside temperature without being retarded or affected by the mass of metal in the shell. On thermometer R there are two contacts c and d which are closed when the mercury reaches a predetermined height. The closure of these contacts establishes a circuit through the small magnet S enclosed in the base, from the plus wire e of a battery, or other current source, to contacts c, d; to post f, to post g and thence through magnet S to minus wire h. The magnet then closes contacts j and k which establishes a circuit from plus wire e, to the dotted-line connection i, thence through contacts j and k to wire m which leads to the aforesaid valve magnet M whose opposite terminal is connected to minus wire h. When the temperature drops sufficiently to cause the opening of contacts c, d, the circuits aforesaid are broken and the magnet M releases the valves 11 and 12 which

are then lifted by spring 10 to their upper position.

Since the valve 11 remains normally closed, the air in duct 9 will be trapped therein at 5 that time putting pressure on cylinder 4. In other words the duct 9 is a normally closed air chamber. That pressure acting on the smaller piston B will move it to the left and the rack C will thereby rotate the shaft E together with stem F of valve G in a direction 10 to turn the steam on the heating pipes of the car. This is what is meant by the statement that the engine is biased to maintain steam on the heating pipes. The purpose of this 15 bias is to insure that failure of the electric current as by the blowing of a fuse or the breaking of the tube of the thermostat or failure of the control valves of the engine will not result in cutting off the steam and 20 leaving the car cold. If, however, the temperature should at any time exceed the predetermined degree, the thermostat will close contacts *c*, *d* and establish the circuits described above. That will cause magnet M to 25 attract its armature, forcing down the stem 18 to close exhaust-valve 12 and open supply-valve 11, thereby admitting air from duct 9 to duct 13 and thence to the rear of the larger piston A. The greater area of piston A will 30 enable it to overcome the opposing force of piston B, and move rack E to the right, thereby closing valve G to shut off steam from the heating pipes in the car. Conversely, when the temperature falls below the predetermined 35 degree, the reverse actions will occur, leaving the valve G in its normal biased position to keep the steam turned on.

To provide for operation of valve G in the event of failure of the thermostat, I provide 40 the armature 15 with an upwardly projecting stem P which enters a recess in a cap Q that screws on the top of the casing of magnet M. In this cap is a thumb-screw N which may be screwed down to engage the stem P and thereby depress armature 15. The effect of this 45 will be to cause the action of valve G, as above described, to cut off the steam, while the reverse movement of the screw N will be to allow armature 15 to rise and restore the normal open position of valve G.

I have provided the engine with means for supporting it, if so desired, on a floor above the valve G, these means being slotted base-lugs 17. Thus in many cases it will only be 55 necessary to remove the usual handle fitting over the squared end of the valve-stem F and replace it by the square socket in the lower end of engine shaft E, setting the engine itself on the floor through which the valve-stem F ordinarily protrudes, and securing it by the base lugs 17. It will be observed that the shell of magnet M is mounted on the cylinder casting of the engine so that the engine and the magnet are practically in one unitary 65 structure. The handles H and N are on the

top of the structure and are readily accessible for use in the respective emergencies above described. In installing the engine it is only necessary to place it in position as described and connect the wires leading from magnet M to the thermostat which will be located at any suitable place in the car.

What I claim as new and desire to secure by Letters Patent is:

1. A fluid pressure valve engine comprising a rotatable shaft provided with valve stem engaging means, a reciprocably mounted operating member engaging said shaft, fluid pressure means for actuating said operating member, and a single magnetically controlled valve controlling said fluid pressure means. 75

2. A fluid pressure valve engine comprising a rotatable shaft provided with valve stem engaging means, fluid pressure actuated means engaging said shaft and operable to convert reciprocating movement into rotary movement, and a single magnetically controlled valve controlling said fluid pressure 80 means. 85

3. A fluid pressure valve-engine comprising a rotatable shaft provided with a valve-engaging socket in one end, a cylinder in which said shaft is mounted, a piston mounted to reciprocate within said cylinder, operating means between the piston and the shaft also within the cylinder to convert movement of the piston into rotary movement of the shaft, and a single magnetically controlled valve controlling the operation of 90 said piston in both directions. 95

4. A fluid pressure valve-engine comprising a cylinder, a piston mounted to reciprocate therein, a rotatable valve-actuating shaft, operating means between the piston and the shaft to convert reciprocating movement of the piston into rotary movement of the shaft, a normally closed air chamber exerting pressure to bias the piston to rotate the valve in one direction and a magnetically controlled valve controlling the operation of 100 said piston. 105

5. A fluid pressure valve-engine comprising a cylinder-casing, a piston mounted to reciprocate within said casing, a smaller piston also mounted to reciprocate within said casing, valve operating means actuated by said pistons, an engine control valve set to normally maintain pressure on the smaller piston and to normally cut off pressure to the larger piston, and an electro magnet controlling the valve pressure to the larger piston. 110 115

6. A fluid pressure valve-engine comprising a rotatable shaft provided with valve-stem-engaging means, two reciprocably mounted actuating pistons of different diameters permanently connected with said shaft, the smaller piston acting to rotate said shaft to valve opening position, a chamber in per- 120 125 130

manent communication with a source of fluid pressure and with the cylinder containing the smaller piston, a control valve for the larger piston, and an electro magnet acting

5 when energized to open the said control valve.

7. A fluid-pressure valve-engine comprising a cylinder and two pistons of different diameters, a rack joining the two pistons, a 10 rotatable shaft carrying a pinion engaging the said rack, a socket on said shaft for receiving the stem of the valve to be operated, means for permanently maintaining fluid pressure on the smaller piston and an electro-magnetically controlled valve for the larger 15 piston acting to admit pressure thereto for closing the operated valve.

8. A fluid-pressure valve-engine comprising a cylinder-casing, pistons of different 20 diameter therein, means whereby the smaller one will act to open and the larger one to close the operated valve, a magnetic shell secured to the cylinder-casing and having ducts which are continuations of corresponding 25 ducts in the said casing, a magnet coil in said shell, and valves in the shell operated by said magnet and a magnet coil for controlling the fluid flow to the larger piston.

9. A fluid-pressure valve-engine comprising 30 a reciprocable piston, a rotary shaft operated thereby, said shaft having means for engaging the stem of the valve to be operated and a single electromagnetic valve for controlling reciprocations of the piston in 35 both directions combined with a thermostat and a magnet controlled by said thermostat and controlling the circuit of the said electromagnetic control-valve.

10. The combination with a fluid pressure 40 valve engine and an electro-magnetic control valve therefor forming part of the engine structure, of a thermostat, a magnet forming part of the thermostat structure and con-

trolled by the thermostat, and a circuit closer in the circuit of said electro-magnetic control valve and controlled by the thermostat magnet. 45

11. A fluid-pressure valve engine having a horizontally reciprocable piston, a vertical rotatable shaft having a socket at its lower end, and a magnet shell mounted on the engine structure and containing an electro-magnetically controlled valve for the engine. 50

12. A fluid pressure valve engine comprising two horizontal reciprocating pistons, a rack connecting the pistons, a vertical rotary shaft having a valve stem connection at its lower end and extending vertically at one side of said rack, a pinion on said shaft engaging said rack, a single electro-magnetic control valve for said engine, said valve being normally positioned to maintain a pressure on one piston and to normally shut off pressure on the other piston, and a thermostat 60 dominating said control valve. 65

13. A fluid pressure valve engine having two reciprocating pistons, one larger than the other, a vertical rotary shaft combined with a valve positioned to be located below 70 the normal plane of the floor of a car, said valve having a vertical stem engaged by said shaft, an electro-magnetic control valve for the larger piston, said electro-magnetic valve being normally positioned to maintain pressure on said smaller piston tending to open the first mentioned valve and at the same time normally shutting off pressure to the larger piston, and a thermostat for intermittently operating the electro-magnetic control valve, 75 whereby actuation of the first mentioned valve is effected. 80

Signed at Albany, in the county of Albany and State of New York, this 13th day of February, 1922.
